CLAIM

The ornamental design for a manual file and sharpening tool, as shown and described.

DESCRIPTION

FIG. 1 is a front elevational view of a manual file and sharpening tool showing our new design, the rear view being a mirror image thereof;

FIG. 2 is a top plan view thereof;

FIG. 3 is a bottom plan view thereof;

FIG. 4 is a right end elevational view thereof; and,

FIG. 5 is a left end elevational view thereof.

Fig.2.

Fig.1.

Fig.3.

Fig.4.

Fig.5.
